ABSTRACT OF THE DISCLOSURE

A duplex arrangement of filter networks has, on the transmitter side, a quarter wave cavity resonator tuned to the transmitter carrier frequency and coupled to the coaxial transmission line in quarter wave spaced relation. A variable quarter wave reactance section is similarly coupled to the line and coats with the resonator to create a condition of antiresonance at the receiver frequency. On the receiver side, a quarter wave resonator and a variable quarter wave section are similarly coupled to the transmission line a quarter wave from the antenna connection, the resonator being tuned to the receiver frequency, and the reactance section coating with the resonator reactance to create a condition of anti-resonance at the transmitter carrier frequency. A line connecting the resonator to the transmission line can be of the same characteristic impedance or, if greater attenuation at a greater frequency separation is desired, of a lower characteristic impedance than that of said transmission line.

CROSS REFERENCE TO A RELATED APPLICATION

This application is a continuation-in-part of my pending application Ser. No. 646,064 entitled "Notch Filter Network" filed June 14, 1967, now abandoned.

BACKGROUND OF THE INVENTION

This invention relates generally to the radio signal filtering art, and more specifically to a new and useful filter network of the notch type.

Notch filters of the distributed element or cavity type, customarily comprise a quarter wave length resonator tuned to resonate at the frequency to be rejected and connected to create a short circuit condition (series resonance) across the transmission line, causing radio energy at that frequency to be reflected back along the transmission line to the source. Notch filters of this type are characterized by a relatively sharp rejection notch compared to wide areas of low attenuation on either side of the rejection notch.

This type filter finds application in the communication field, particularly in the frequency range of 30-3000 MHz and in the filter duplexer. This device allows the simultaneous operation on one antenna of two pieces of equipment operating on two different frequencies. Such equipment usually comprises a paired transmitter and receiver, which impose the most stringent filtering requirements.

The duplexer comprises a number of filter sections spaced along two coaxial transmission lines which lead from a common antenna terminal to each of the equipment terminals. The purpose of the filter sections on the receiver branch is to isolate the receiver from the transmitter carrier. The receiver frequency will pass by these filters allowing energy at the receiver frequency from the antenna to pass to the receiver with little attenuation. The pass band of these filters being wide compared to the rejection notch, other nearby transmitter carriers close

2

to the receiver frequency may also enter the receiver causing desensitization or intermodulation problems. This poses an obvious problem not only in duplexers but in receivers generally.

5 The purpose of the filters on the transmitter branch of the duplexer is to pass the transmitter carrier and reject transmitter noise at the receiver frequency and over as wide a range about the receiver frequency as possible. This energy is reflected back and forth between the transmitter and successive filter sections and dissipated as heat. Being very low power relative to the transmitter carrier, the heating effect is minute.

The desired width of the rejection notch is determined by two factors, the selectivity of the receiver and the relative noise output of the transmitter. The limitation on minimum separation of duplexer carrier and receiver frequencies is determined by the ability of the duplexer to maintain sufficient isolation or rejection of all frequencies in the transmitter noise spectrum occurring within the 15 pass band of the receiver. The filter sections on both branches of the duplexer contribute to this because it is the ability to reject frequencies midway between the two duplexer frequencies which now becomes very important. At the same time, it would be desirable to position such 20 carrier and receiver frequencies as close together as possible, to conserve the frequency spectrum and thereby make it possible for more persons to operate within a given range in a given area.

SUMMARY OF THE INVENTION

A primary object of this invention is to provide an improved radio frequency filter network of the notch type, permitting a significantly closer spacing between the transmitter and receiver frequencies in a duplex operation.

35 It is also an object of this invention to provide the foregoing in a duplex arrangement less subject to interference from neighboring transmitters.

Another object of this invention is to provide the foregoing in a relatively simple and inexpensive arrangement 40 which can be readily adjusted in the field without special equipment.

In one aspect thereof, the filter network of this invention is characterized by the tuning to a quarter wave length resonator to the frequency to be passed, in conjunction with a reactance coating with a resonator reactance to create a condition of antiresonance tuned to the frequency to be rejected and arranged to effectively short circuit the same.

45 50 55 60 In one aspect thereof by the provision, on the transmitter side, of a quarter wave resonator and a reactance coupled to the transmission line in quarter wave spacing relative thereto, the resonator being tuned to resonate at the transmitter carrier frequency and the reactance coating with the reactance of the resonator to create a condition of antiresonance at the receiver frequency. On the receiver side, a quarter wave resonator and a reactance are coupled to the transmission line in quarter wave spacing relative thereto, the resonator being tuned to the receiver frequency and the reactance coating with the reactance of the resonator to create a condition of anti-resonance at the transmitter carrier frequency.

The foregoing and other objects, advantages and characterizing features of my invention will become clearly apparent from the ensuing detailed description of an illustrative embodiment thereof, reference being made to the accompanying drawing.

BRIEF DESCRIPTION OF THE DRAWINGS

70 FIG. 1 is a graphical representation comparing the performance of a filter network of the instant invention with

that of a conventional notch filter, as viewed between the antenna and equipment terminals;

FIG. 2 is a diagrammatic circuit representation of a filter network of this invention;

FIG. 3 is a diagrammatic circuit illustration of a duplexer arrangement incorporating a filter network of FIG. 2 in accordance with my invention;

FIG. 4 is a graphical representation comparing the performance of a duplexer using filter networks of this invention with that of a duplexer using conventional notch filters, as viewed between the transmitter and receiver terminals; and

FIGS. 5-7 are graphical representations illustrating the performance of a filter network of the instant invention and compared with that of a conventional bandpass filter, in response to a variation in tuning.

DETAILED DESCRIPTION OF THE ILLUSTRATED EMBODIMENTS

FIG. 1 shows the attenuation curve 11 of a filter network constructed in accordance with my invention, as contrasted with the attenuation curve 12 of a conventional notch filter, under the same conditions. f_o represents the frequency to be passed, while f_r represents the frequency to be rejected. The conventional notch filter is tuned to resonate at f_r and to create a short circuit condition across the transmission line at this point. It will be noted that a relatively narrow notch is provided, with a sharp drop off in attenuation at frequencies between f_o and f_r including frequencies very close to the latter. The pass band, comprising the plateau extending to the left from f_o (or to the right from the other side of the notch) is quite broad. This, too, presents a problem because of the possibility of interference with and from neighboring transmitters.

With my invention, however, the filter network is tuned to resonate at the frequency to be passed, namely f_o . Turning now to FIG. 2, there is shown a filter network of this invention comprising a co-axial transmission line 1 to which is coupled a resonator 2 and a reactance 3. Resonator 2 and reactance 3 are coupled to transmission line 1 at point A, by a coupling line 4 comprising, in this instance, a section of co-axial cable. Both resonator 2 and reactance 3 are connected in parallel to a coupling line 4 at point B, which is spaced along line 4 from point A a distance equal to substantially one quarter wave length of the frequency to be passed.

Resonator 2 can be any suitable quarter wave length resonator, comprising in the illustrated embodiment a resonating cavity of known design, arranged to be tuned by a conventional tuning means 5, all in a manner well known in the art. The outer shell of resonator 2 is grounded, as is customary. For best results, cavity resonator 2 has a high-Q factor, on the order of 6,000-7,200 for operation in the 150 mc. band, and 10,000 for operation in the 400 mc band. It is a particular feature of this invention that, whereas the resonator 2 conventionally would be connected to line 1 at point A and tuned to the frequency to be rejected (f_r), it is instead spaced one quarter wave length from transmission line 1 and tuned to resonate at the frequency to be passed (f_o). As a result, at f_o resonator 2 creates a short circuit effect at point B and inversely a high impedance at point A which latter is ignored by the signal at frequency f_o .

Because resonator 2 is tuned to f_o a notch effect is obtained at the frequency to be passed, as clearly shown in FIG. 1 and as contrasted with the relatively broad pass band of a conventional notch filter.

In the illustrated embodiment, reactance 3 comprises a conventional variable quarter wave section of co-axial cable which can be either open or closed, and which is tunable, as indicated in a manner well known in the art. Reactance 3 could instead be a capacitor or inductor, of known design. It is tuned against resonator 2 to coat with

the reactance of resonator 2 to create, at point B, a condition of antiresonance at the frequency to be rejected f_r . As a result, the combined, tuned reactance of resonator 2 and member 3 creates a short circuit effect at point A, causing the undesired frequency f_r to float back and forth until it has been dissipated in the form of heat. At low energy levels, the heat thus produced usually poses no problem.

A high level of attenuation occurs at f_r . In addition, and of particular importance is the relatively greater attenuation at frequencies adjacent f_o . For example, looking at FIG. 1 the attenuation at a frequency displaced 0.1 mc. to the right of f_o , toward f_r , is over three times as great with the filter network of this invention as with the conventional notch filter. This relatively greater attenuation caused by the sharper drop off from f_o in the attenuation curve toward f_r , means that f_r can be spaced significantly closer to f_o than heretofore. In effect, the reject notch is broadened, to attenuate frequencies on either side of f_r . Simultaneously, the pass band is inversely notched, to attenuate frequencies on both sides of f_o and thereby reduce the likelihood of interference with neighboring stations.

It is a particular feature of my invention that the response characteristics of the filter can be varied by varying the coupling of cavity 2 to point B. This can be accomplished by varying loop 10. For example, decreasing the effective coupling area of loop 10 will cause the notch at f_o to become sharper, and the notch at f_r to become broader and possibly deeper, resulting in a steeper rate of descent from f_o to f_r .

The filter network of FIG. 2 also can be tuned to reverse the relative positions of f_o and f_r . This is done in a duplexer arrangement. Such reverse tuning creates a mirror image of response curves 11 and 12, as shown at 11' and 12' in FIG. 1.

It will be noted that the attenuation curve 11 in FIG. 1 indicates a frequency separation between f_o and f_r of about 0.250 mc. and an attenuation of about 25 db. This response characteristic was obtained with coupling line 4 and transmission line 1 being of the same characteristic impedance, for example both lines consisting of standard 50 ohm cable.

When the filter network of the present invention is operated in different frequency bands, a change in the frequency separation between f_o and f_r sometimes is required. For example, certain operating conditions require a relatively greater frequency separation between f_o and f_r such as in the order of 4 to 5 mc. Without changing the size of cavity 2, operation of the filter network can be optimized for such changes in the following manner.

A greater attenuation at a greater frequency separation relative to that of the characteristic shown in FIG. 1 can be obtained by lowering the impedance of coupling line 4 relative to that normally present in the filter network and system in which it is included. In a particular example, the quarter wave cable 4 was constructed of solid air line having a lower characteristic impedance than that of the standard 50 ohm cable in the transmission line and associated system. An air line constructed for application at a frequency separation of 4-5 mc. between f_o and f_r , for example, can include a tubular, outer conductor of brass having an outer diameter of about 1.5 inches and a thickness of about 0.05 inch and an inner conductor having an outer diameter of about 1½ inches. The outer conductor inner surface is silver plated as is the outer surface of the inner conductor. This particular air line has a characteristic impedance of about 13 ohms.

The reduced losses in the large air line plus the quarter-wave transforming action of a high impedance to a much lower impedance, i.e., the short circuit isolation at f_r , provides a relatively larger attenuation at the greater frequency separation between f_o and f_r . This optimization of the filter network at changed operating conditions is provided while at the same time maintaining the sharp attenuation of frequencies on both sides of f_o and there-

by reduce the likelihood of interference with neighborhood stations.

FIG. 3 illustrates a duplex arrangement utilizing the filter network of FIG. 2 in accordance with my invention. A transmitter 6 is connected to an antenna 7 by a first co-axial transmission line 8, and a receiver 9 is connected to the same antenna 7 by a second transmission line 10. The problem is to prevent the transmission of transmitter "noise" to the receiver 9 at the receiver frequency, and to prevent desensitization of the receiver by the transmitter carrier. This problem is complicated by the fact that the transmitter carrier frequency and the receiver frequency should be spaced as closely together as possible. This is accomplished in accordance with my invention by arranging filter networks of the type shown in FIG. 2 in the duplexer arrangement of FIG. 3, as follows.

On the transmitter side, a quarter wave resonator 2 is connected at B to a quarter wave co-axial coupling line 4 which is in turn connected to transmission line 8 at A, and a variable quarter wave reactance 3 also is connected to line 4 at point B, as described in connection with FIG. 2.

The resonator 2 is tuned to the transmitter carrier frequency, which in this instance is the frequency to be passed f_o . The reactance 3 is tuned against resonator 2 so that its reactance, in conjunction with that of resonator 2 creates a short circuit condition at A at the receiver frequency, which on the transmitter side is the frequency to be rejected f_r .

On the receiver side, the same type of filter network is used, the various parts being distinguished from the corresponding network on the transmitter side by the use of primes on the corresponding reference numerals. Resonator 2' is tuned to resonate at the receiver frequency which on the transmitter side was the "noise" frequency f_r to be rejected but on the receiver side is the frequency to be passed f_o . Since co-axial coupling line 4' spaces point B' substantially a quarter wave length from the point of connection A' to transmission line 10, resonating of cavity 2' creates a high impedance at point A' permitting the receiver frequency to pass. Reactance 3' coacts with resonator 2' as previously described to create a short circuit condition at point A' at the transmitter carrier frequency which on the transmitter side was the frequency to be passed f_o but on the receiver side is the frequency to be rejected f_r . Connection point A' is spaced from the point of connection to antenna 7 substantially one quarter wave length of the carrier frequency and the short circuit condition at A' as the transmitter carrier is transformed to a high impedance at the antenna junction which when connected in parallel with the matched load at the antenna junction, has substantially no effect on transmission of transmitter power to the antenna. Thus, on the receiver side, the response curve is the mirror image of that shown in FIG. 1 except that f_o would represent a receiver frequency and f_r the transmitter carrier frequency. The highly desirable characteristics of each filter network thus function to permit f_o and f_r to be positioned much more closely than before.

The filter network of this invention is particularly effective in a duplexer arrangement because of the relatively greater attenuation provided over the frequency range between the carrier and receiver frequencies. This is clearly evident from a comparison of the attenuation levels at the points of intersection of the mirror image curves in FIG. 1. The additive result of curves such as these is shown in FIG. 4 where curve 13 represents the operating characteristics of a duplexer incorporating a total of six filter networks of this invention (three on each side) and curve 14 represents the operating characteristics of the same duplexer incorporating a total of seven conventional notch filters (four on the transmitter side). In the frequency range between the carrier and receiver frequencies, the minimum attenuation provided by the duplexer having the filters of this invention is over twice that of the other.

Usually, additional filter networks will be provided on either side, spaced apart one quarter wave, for even greater attenuation of transmitter carrier and transmitter noise on and about the receiver frequency.

Connecting lines 4 and 4' together with transmission lines 8 and 10 all are of the same characteristic impedance when an extremely close spacing between transmitter carrier and receiver frequencies is desired. When, on the other hand, a relatively larger frequency separation, such as about 4-5 mc., is required by a change in operating conditions, connecting lines 4 and 4' each can have a characteristic impedance lower than that of transmission lines 8 and 10. For example, connecting lines 4 and 4' each can comprise a solid air line having a characteristic impedance of about 13 ohms and transmission lines 8 and 10 can comprise standard 50 ohm cable. This optimizes operation of the filter networks for the change in operating condition while reducing the likelihood of interference in a manner similar to that as described in connection with the single network of FIG. 2.

FIGS. 5-7 illustrates the performance of a filter network of the instant invention wherein reactance 3 coacts with resonator 2 to create two short circuit conditions at point A on transmission line 1, which are symmetrically disposed about the filter pass frequency. This is accomplished by a variation in tuning of the basic assembly, on a cavity with an unloaded Q relatively lower, for example about 2300, than the unloaded Q of the cavity to which the circuit was applied in obtaining the curves of FIGS. 1 and 4, which was about 7,000. The result is a change in the form of the response with the filter being tuned for a pass frequency and two rejected frequencies.

Referring now to FIG. 5, the attenuation curve 20 of the filter of the present invention is contrasted with the attenuation curve 21 of a conventional bandpass filter. Both filters were coupled to their respective cavities for the same loss or attenuation at the frequency to be passed, f_o , which in this example is about 460 mHz. The two cavities identically coupled for the same loss also had the same unloaded Q which was about 2300. The filter of the present invention has two relatively sharp rejection notches indicated at f_{r1} and f_{r2} in FIG. 5 and occurring at about 457 and 463 mHz., respectively. The fact that this performance from a single filter includes two rejections closely spaced to and on each side of the frequency to be passed, f_o , is of particular significance for use in multi-coupling where a large number of closely-spaced frequencies are present.

FIG. 6 illustrates the effect of varying the insertion loss by changing the coupling on the performance of the filters from which the curves of FIG. 5 were derived. The new attenuation curve of the filter of the present invention is shown at 20', and the attenuation curve for the bandpass filter is shown at 21'. The filter of the present invention still has two relatively sharp rejection notches, indicated at f_{r1}' , and f_{r2}' , and the effect of increasing the coupling to the cavity is to increase the respective spacing between the rejection notches and f_o .

FIG. 7 includes the two attenuation curves 20 and 21' of the filter of the present invention on the same plot to illustrate more clearly the effect of a change in the coupling to the cavity.

Accordingly, it is seen that my invention fully accomplishes its intended objects, providing much greater attenuation of frequencies about the duplexer operating frequencies, permitting a significantly closer spacing between the transmitter carrier frequency and the receiver in a duplex arrangement, and significantly reducing the likelihood of interference from neighboring stations whether used in a duplexer or for single equipment filtering.

Having fully disclosed and completely described my invention, what I claim as new is:

1. A notch type filter network designed to pass and reject closely spaced frequencies comprising, in combina-

tion with a transmission line, a quarter wave length resonator, a line connecting said resonator to said transmission line, said connecting line having a length substantially equal to one quarter wave length of the frequency to be passed, said resonator being tuned to resonate at the frequency to be passed, and reactance means similarly connected by said connecting line to said transmission line and in parallel with said resonator, said reactance means coacting with said resonator to create a condition of antiresonance in substantially one quarter wave length relation to said transmission line at the frequency to be rejected.

2. A filter network as set forth in claim 1, wherein said reactance means comprises a variable quarter wave length section.

3. A filter network as set forth in claim 1, wherein said reactance means comprise a shorted stub.

4. A filter network as set forth in claim 1, wherein said reactance means comprises a shorted stub.

5. A filter network as set forth in claim 1, wherein said resonator comprises a high-Q cavity resonator.

6. A filter network as set forth in claim 1, wherein said transmission line comprises a co-axial cable.

7. A filter network as set forth in claim 1, together with variable means coupling said resonator to said connecting line.

8. A filter network as set forth in claim 1 wherein said connecting line has a lower characteristic impedance than that of said transmission line.

9. A filter network as set forth in claim 8 wherein said connecting line comprises a solid air line.

10. A notch type filter network designed to pass and reject closely spaced frequencies comprising, in combination with a transmission line, a high-Q resonator, a line connecting said resonator to said transmission line, said connecting line having a length substantially equal to one quarter wave length of the frequency to be passed, said resonator being tuned to resonate at the frequency to be passed, and reactance means similarly connected by said connecting line to said transmission line, said reactance means coacting with said resonator to create a condition of antiresonance in substantially one quarter wave length relation to said transmission line at the frequency to be rejected.
